(57)

CLAIM

The ornamental design for a charging connector, as shown and described.

DESCRIPTION

FIG. 1 is rear perspective view of the charging connector. FIG. 2 is a rear view of the charging connector of FIG. 1. FIG. 3 is a front view of the charging connector of FIG. 1. FIG. 4 is a right side view of the charging connector of FIG. 3.

FIG. 5 is a left side view of the charging connector of FIG. 3.

FIG. 6 is a top view of the charging connector of FIG. 1; and, FIG. 7 is a bottom of the charging connector of FIG. 1. The broken lines in the figures represent environmental subject matter which forms no part of the claimed design.

1 Claim, 4 Drawing Sheets(56)
